J. H. Braddock
ATTORNEY.

UNITED STATES PATENT OFFICE.

ANDREW L. RIKER, OF FAIRFIELD, CONNECTICUT.

VENTILATOR.

Application filed December 19, 1924. Serial No. 756,912.

This invention relates to a ventilator, useful for many purposes, but more especially adapted for use as a closure for transoms, doorways, windows, panels, or the like.

5 An object of the invention is to provide a ventilator of the general nature of those described and illustrated in my Patents, No. 1,519,553, granted December 16, 1924, and No. 1,529,037, granted March 10, 1925; and 10 presenting advantageous characteristics and features of construction which are improvements over the disclosures of said patents.

A further and more specific object is to provide a ventilator consisting of a frame 15 having a plurality of louvers pivoted therein to turn on their axes and so constructed and mounted that when swung in one direction they will completely and positively close the space within the frame, and when swung in 20 the other direction will leave passage ways of the maximum dimensions possible between the respective louvers without opening a direct line of vision through the frame.

25 A still further object is to provide a ventilator as just stated and having dependable operating mechanism for manipulating all of the louvers to open or closed positions, the operating mechanism including a practical arrangement limiting the degree to which 30 the louvers can be turned on their pivots.

With the above and other objects in view, the invention comprises the construction, arrangement and combination of parts as now 35 to be fully described and as hereinafter to be specifically claimed, it being understood that the disclosure herein is merely illustrative of the principles and meant in no way to limit the spirit of the invention, changes 40 in details of construction and arrangement of parts being permissible so long as within the scope of the appended claims.

In the accompanying drawing forming a part of this specification,

45 Fig. 1 is an elevational view of the novel ventilator, showing the louvers in open position;

Fig. 2 is an enlarged horizontal, longitudinal sectional view, taken as on line 2—2 in Fig. 1, looking in the direction of the arrows;

Fig. 3 is a similar sectional view, but disclosing the louvers in closed position;

Fig. 4 is a vertical sectional view, taken as on line 4—4 in Fig. 2, looking in the direction of the arrows;

Fig. 5 is an enlarged sectional view of one

end portion of the ventilator, detailing the mechanism for operating the louvers;

Fig. 6 is a sectional view, taken as on line 6—6 in Fig. 5, looking in the direction of 60 the arrows; and

Figs. 7 and 8 are enlarged sectional views, Fig. 7 showing a fragment of a louver and the upper frame member in which the louver is mounted, and Fig. 8 showing a 65 fragment of a louver and the lower frame member in which the louver is mounted, said Fig. 8 showing also the operating bar and its manner of association with the louvers, both views being taken as on line 8—8 in 70 Fig. 2, looking in the direction of the arrows.

The ventilator of this invention is constituted by a frame of rectangular configuration, spaced apart louvers pivotally mounted therein, end louvers fixed in the frame, and mechanism for swinging the pivoted louvers on their pivots to open or close the space within the frame.

The frame may be composed of sheet 80 metal, and may consist of oppositely disposed members denoted 10, 11 and 12, 13, respectively. All of the members of the frame may be plates having flanges upon their opposite edges, the flanges of the members 10 85 and 11 being denoted 14 and 15, respectively, and the flanges of the members 12 and 13 being denoted 16 and 17, respectively.

The manner in which the members 10, 11, 12 and 13 are preferably joined is best shown 90 in Figs. 2, 3, 4 and 5, wherein end portions of members 12 and 13 and their flanges 16 and 17 are drawn or offset inwardly as denoted at 18, and the flanges 14 and 15 of the members 10 and 11 fit snugly over the drawn 95 or offset portions 18 to align with the flanges 16 and 17. The connections between the members 10, 11 and 12, 13, respectively, may be each made by means of a rivet 19 passing through said flanges 14 or 15 and through drawn in or offset portions 18, a bushing, 20, extending between the drawn in or offset portions and through which the rivet extends, serving to allow the rivet to clamp the portions 18 and flanges 14 or 15, 100 as the case may be, against each other.

By the provision of elongated slots (not shown) in the drawn in or offset portions or in the flanges themselves, the members can be 110 slightly adjustable with respect to each other, as will be understood. For convenience, I have in the drawing designated all

of the drawn in or offset portions 18, all of the rivets 19, and all of the bushings 20, the connections between all of the plates desirably being made in the same manner.

5 The flanges and their drawn in or offset portions are preferably perpendicular to the members 10, 11, 12 and 13, respectively, and all of the flanges extend inwardly of the frame. The ends of certain of the frame members are desirably contiguous with or 10 closely adjacent to the bodies of other frame members. See Fig. 4.

The ventilator includes a plurality of spaced apart louvers pivotally mounted 15 therein, and two end louvers fixed in the frame adjacent the outermost of the pivoted louvers. All of the louvers are preferably composed of sheet metal. As disclosed, they are mounted in the frame to be perpendicular 20 to the members 10 and 11 and parallel with the members 12 and 13, and all of the pivoted louvers are of L-shape.

The pivoted louvers, denoted 21, are spaced at equal distances apart. Each has an ear 22 upon its arm 23 pivoted upon the member 10, and an ear 24 upon this same arm pivoted upon the member 11, the arm 25 of each louver 21 being free of ears. The ears 22 and 24 preferably extend at right-angles in the same direction from the planes of the arms 23 of the louvers 21, the ears 22 being situated entirely within the space between the arms 23 and 25, and the ears 24 having extensions 26 projecting beyond said space for a purpose to be explained.

The pivoted louvers are mounted in the members 10 and 11 in the manner best shown in Figs. 2, 3, 7 and 8. That is to say, each of the ears 22 is provided with a hole rotatably receiving a drawn portion 27 of the metal of the member or plate 10 of the frame, and each of the ears 24 is drawn as at 28 to rotatably enter an annular flange 29 consisting of upwardly drawn metal of the member or plate 11 of the frame, the pivotal points for the louvers being arranged adjacent the opposite ends of the arms 23 thereof, not far from the midwidths of said arms as shown.

50 The ears 24 extend beyond the pivotal points of the arms 23 upon the member 11, as represented at 26 and hereinbefore referred to as extensions of the ears 24. 30 represents an operating bar for manipulating the pivoted louvers. The operating bar 55 is arranged beneath the extensions 26 of the ears 24 to slide upon the plate 11 of the frame and each of the extensions 26 has metal drawn therefrom and rotatably entering holes 31 at uniform distances apart in the operating bar.

Numerals 32 and 33 denote end louvers fixed in the frame in any suitable manner. The body portion of louver 32 is preferably 65 arranged contiguous with the rear drawn

in or offset portions 18 at the left end of the ventilator, and the body portion of louver 33 is preferably arranged contiguous with rear portions 18 at the right end of said ventilator. The outer side edges, denoted 34 and 35, of said louvers 32 and 33, respectively, desirably engage the inner faces of members or plates 12 and 13, respectively, and the inner edges of said louvers 32 and 33 terminate within the frame beyond the flanges thereof. The portion, denoted 36, of the louver 32 extending beyond the flanges 16 is disposed obliquely and from rear toward front of the frame, and the portion, denoted 37, of the louver 33 extending beyond the flanges 17 includes a part 38 which is straight projection of the louver 33 and in the plane of its edge 35, and a part 39 at right-angles, approximately, to the part 38 and projecting for a short distance from the rear toward the front of the ventilator. As disclosed, the fixed louvers 32 and 33 are held in position by the rivets 19 and bushings 20. Additional fastenings means (not shown) could, however, consist of ears upon said stationary louvers and fixed to the upper and lower members or plates 10 and 11.

The mechanism for moving the operating bar longitudinally to turn the pivoted louvers on their pivots in a manner which will be obvious, consists of a spindle 40 mounted in the flanges or their drawn in or offset portions adjacent a corner of the ventilator and having a crank 41 and a manipulating handle 42. Near one of its ends the operating bar is bent to general U-shape as denoted at 43 to receive the crank, and the position of that end of the bar, denoted 44, beyond the spindle, may be insured by a bushing 20, already described, situated directly above and close to the operating bar.

The metal of the flanges may be drawn as denoted at 45 to provide a dependable bearing for the spindle 40, and the U-shaped part of the operating bar is preferably arranged about the crank so that the slight forward and rearward movements of the operating bar when moved longitudinally to adjust the louvers impart slight endwise movements to the spindle. Evidently, the operating bar will thus insure the spindle against displacement. The spindle has a reduced end 46 mounted in a bearing 45 whereby the larger diameter of the spindle can limit rearward movement of the same. Forward movement of the spindle is checked by engagement of the operating bar with the front flange of the member 11. Obviously, the position of the spindle in its bearing is thus insured.

In the drawing I have shown the fixed louver 33 as having a longitudinal slot 50 in its lower end to be positioned about the spindle 40. See Fig. 5. The arrangement as illustrated is for convenience in assembling the elements of the ventilator.

The throw of the crank 41 determines the distance the operating bar can move longitudinally, and hence limits the degree to which the pivoted louvers can be turned on their pivots.

In assembling the louvers with the frame members 10 and 11, I desirably utilize rivets 47 as shown in Fig. 7 to first secure the ears 22 to the frame member 10. I then associate ears 24 with the frame member 11 in the manner already set forth and I may utilize rivets 48 as shown in Fig. 8, to insure the relative positions of the ears 24 and the frame member 11.

By drawing the metal of the frame member 11 upwardly to form the annular flanges 29, I provide a space 49 between the extensions 26 of the ears 24 and the frame member 11 to afford clearance for the longitudinal sliding movements of the operating bar upon the frame member 11. This will be most clear from Fig. 8.

The manner in which the ventilator functions will be clear from the description and drawing. When the handle 42 is as disclosed in Fig. 2 (at one end of the stroke of the operating bar 30), the pivoted louvers are in wide open position. At this time, the arms 23 and 25 of said pivoted louvers are all at angles of about 45° to the rear and front, respectively, of the frame. The distance between each louver and those adjacent it is just insufficient to allow a direct line of vision through the frame when the pivoted louvers are in wide open position, and the fixed louvers 32 and 33 are at proper distances from the outermost pivoted louvers so that there will be no direct line of vision between outermost louvers and said fixed louvers. By the provision of L-shaped louvers, passage ways of the maximum dimensions possible are procured when the louvers are in open position.

When the handle 42 is as disclosed in Fig. 3 (at the opposite end of the stroke of the operating bar), the full length of the outer edge of arm 25 of each pivoted louver, except the left, outermost one, interlaps with the full length of the inner edge of the arm 25 of the louver directly to the left and adjacent it, as indicated at 51. The arm 25 of said left, outermost louver engages the full length of the inner edge of the oblique portion 36 of fixed louver 32, as indicated at 52, while the arm 23 of the right, outermost pivoted louver engages the full length of the adjacent face of the part 39 of the fixed louver 33, as indicated at 53. All of the arms 25, as disclosed, are parallel, or nearly parallel, with the front face of the frame, while the arms 23 are approximately perpendicular to said front face.

While the L-shaped louvers mounted in the manner set forth permit passage ways of maximum dimensions, yet when the

pivoted louvers are closed there is substantial engagement of the louvers with each other to provide positive closings between all of the pivoted louvers. The rear face of the arm 25 of the left, outermost louver 70 is engaged by the inner edge of the fixed louver 32 so that the closing here is also positive. The arm 23 of the right, outermost louver engages approximately the full width of the part 39 of the fixed louver 33 so that 75 this closing is likewise positive.

The ventilator as illustrated and described is of very simple construction. The frame consists of but four sheet metal plates rigidly secured to each other. Each pivoted 80 louver with its ears consists of a single piece of sheet metal bent to L-shape and mounted in the frame. Each fixed louver is likewise a single piece of metal. The operating mechanism consists of an operating bar and 85 crank with manipulating handle. The elements going to make the ventilator are relatively few and the positions of all of the elements are positively insured, no liability whatsoever existing that any element can become dislocated or impaired. Hence, the 90 ventilator is durable, reliable and efficient for a long period of time.

To incorporate the ventilator in its position of use, all that is necessary is to fit the 95 frame into an opening, the flanges of the frame members 10, 11, 12 and 13 serving the purpose of inclosing the ends of all of the louvers and interlapping with the fixed 100 louvers to preserve the advantageous features of the ventilator.

Having thus fully described the invention, what I claim as new and desire to secure by Letters Patent is:

1. As an article of manufacture, a device 105 comprising a rectangular frame consisting of joined metallic channel pieces, pivoted L-shaped metallic louvers having integral ears upon their opposite ends, said ears being mounted in certain channel pieces of 110 said frame between marginal portions of said channel pieces, and fixed metallic louvers associated with certain channel pieces between marginal flanges thereof, and means for swinging the pivotally mounted 115 louvers upon their pivots to close or to open passageways between the respective louvers, said fixed louvers being supported adjacent a face of said frame, and said means for swinging the pivoted louvers including an 120 operating bar situated adjacent a face of said frame and opposite said fixed louvers, whereby said fixed louvers can offer no interference to manipulations of said operating bar. 125

2. As an article of manufacture, a device comprising a rectangular frame consisting of joined metallic plates having flanges upon their opposite edges all extending inwardly beyond the body of the frame, certain of 130

4
said flanges having offset portions fitted within others of said flanges, louvers mounted in certain of said plates and between said flanges, there being intermediate 5 L-shaped louvers all pivotally mounted and end louvers fixedly mounted, said end louvers each being mounted between the flanges of one of said metallic plates and contiguous with certain offset portions 10 thereof, a bushing extending between each fixed louver and an offset portion of said one metallic plate spaced from said fixed

louver, and means extending through said bushing, fixed louver, offset portions, and flanges of a metallic plate in which said offset portions are fitted to clamp said fixed louver against the offset portions with which it is contiguous and to clamp said offset portions and the flanges fitted about said offset portions against each other, respectively. 15 20

Signed at Bridgeport, in the county of Fairfield, and State of Connecticut, this 18th day of December, A. D., 1924.

ANDREW L. RIKER.
